JAMES LESLIE CAMPBELL, OF WEST ADELAIDE, SOUTH AUSTRALIA, AUSTRALIA

MACHINE FOR MOLDING PLASTIC MATERIAL

No. 887,720.

Specification of Letters Patent.

Patented May 12, 1908.

Application filed August 5, 1907. Serial No. 387,159.

To all whom it may concern:

Be it known that I, JAMES LESLIE CAMPBELL, a subject of the King of Great Britain and Ireland, residing at Roebuck street, 5 West Adelaide, State of South Australia, Commonwealth of Australia, have invented a certain new and useful Improved Machine for Molding Plastic Material, of which the following is a specification.

10 My invention is an improved machine for molding plastic material into lengths of any desired section, and it has been designed especially for manufacturing lengths of core as used in foundry work and lengths of clay adapted to be cut into bricks.

15 My invention comprises a tubular body or "former" with a feed hopper over an opening in same, a reciprocatable plunger within such "former", and means for operating the 20 plunger, all mounted upon a suitable bed.

In order that my invention may be clearly understood I will describe the same with reference to the accompanying drawings in which—

25 Figure 1 is a side view of my improved machine. Fig. 2 is a plan view of same. Fig. 3 is a vertical central longitudinal section. Fig. 4 is a vertical central cross section. Fig. 5 is a plan view of the bed alone.

30 The "former" consists of a tubular body A having an internal cross section of the shape of the required length of material. A separate "former" is required for each variation in shape and size of cross section. In the 35 upper portion of this tubular body is an opening over which is arranged a hopper B for holding the plastic material and through which it may be pressed down into the tube either by hand or by mechanical means as preferred. The plunger C is of size and shape to approximately fit and slide easily within the "former" and when used in core making has upon its forward or operative end a spike C¹ of suitable size to make a vent hole 40 through the length of core.

45 The means for operating the plunger consists of some suitable device whereby a reciprocating movement may be given to the plunger. In the drawing I show a rack bar D and toothed sector E with handle, or the plunger may be connected to a disk or crank operated by means of a pulley. The rear end of the plunger is attached to the front end of the rack by a bolt F passing through 50 an eye in the plunger and through a vertical slot in the rack the vertical slot permitting

of the attachment of different sized plungers. The toothed sector is mounted upon a pin H carried by lugs rising from the bed K.

As shown in the drawings the tubular body A is mounted upon the bed K by means of an intermediate block M. This block has a flat bed with holes fitting over two studs K¹ K¹ projecting upwards from the bed K. On its top side it has two lugs M¹ M¹ with 60 holes to take the tube A. A separate intermediate block is required for each tube of different shape or size in cross section. The portions of the tube which are bent outwards to form the feed opening, as shown in Fig. 4, 65 fit neatly between the lugs M¹ M¹ and assist in holding the tube firmly in position in the block. The hopper, and with it the intermediate block, is clamped down to the bed by a clip B¹ on one side and a pivoted eccentric 70 catch B² on the other fitting beneath projecting flanges K² K² on the bed.

75 The length of material may be made of round, square or other cross section it being necessary to have a separate tube or "former" and separate plunger for each size and shape of cross section.

80 In operation the plastic material is pressed down through the hopper into the tube and as the plunger is reciprocated it drives the material through the delivery end of the tube on to a receiving tray (not shown in the drawing). By the repeated movement of the plunger any required length of material is produced having the external shape and 85 size of the hole through which it is forced. This length may then be cut into shorter 90 lengths as required by hand or by mechanical means.

Having now fully described and ascertained my said invention and the manner in which it is to be performed I declare that what I claim is—

95 1. A machine for molding plastic material comprising a tubular body or former having 100 a longitudinal feed opening, the sides of the former adjacent the opening being turned outwardly to form flanges, a bed, a block resting on the bed and provided with end lugs having openings through which the ends 105 of the former project, the ends of the out-turned edges of the feed opening engaging the inner faces of the lugs, a plunger provided with a core pin movable through the former, a rack bar provided with a transverse slot, a pin traversing the slot and the 110 adjacent end of the former, and a toothed

- sector pivoted to the bed and meshing with the teeth of the rack bar, said sector being provided with a handle for convenience in manipulating the same.
- 5 2. A machine for molding plastic material comprising a tubular body or former having a longitudinal feed opening, the sides of the former adjacent the opening being turned outwardly to form flanges, a bed, a block 25 resting on the bed and provided with end lugs having openings through which the ends of the former project, the ends of the outturned edges of the feed opening engaging the inner faces of the lugs, a plunger movable through the former, a rack bar provided with a transverse slot, a pin traversing the slot and the adjacent end of the former, and a toothed sector pivoted to the bed and meshing with the teeth of the rack bar, said sector 30 being provided with a handle for convenience in manipulating the same.
- 10 15 20
3. A machine for molding plastic material, comprising a tubular body or former, having a longitudinal feed opening, the sides of the former adjacent the opening being turned outwardly to form flanges, a bed, a block on the bed, and provided with end lugs having openings through which the ends of the former project, the ends of the outturned edges of the feed opening engaging the inner 35 face of the lugs, a plunger movable through the former, and means for operating the plunger.

In testimony that I claim the foregoing as my invention I have signed my name in the presence of two subscribing witnesses this twelfth day of June 1907.

JAMES LESLIE CAMPBELL.
